(57) **CLAIM**

The ornamental design for an attachment piece for time-sensitive articles, as shown and described.

DESCRIPTION

FIG. 1 is a right front perspective view of an attachment piece for time-sensitive articles, showing our new design in a wrapped configuration;

FIG. 2 is a front elevational view thereof;

FIG. 3 is a left side elevational view thereof;

FIG. 4 is a right side elevational view thereof;

FIG. 5 is a top plan view thereof;

FIG. 6 is a bottom plan view thereof;

FIG. 7 is a back elevational view thereof;

FIG. 8 is a right front perspective view of the attachment in an unwrapped configuration in accordance with an embodiment;

FIG. 9 is a front elevational view thereof;

FIG. 10 is a left side elevational view thereof;

FIG. 11 is a right side elevational view thereof;

FIG. 12 is a top plan view thereof;

FIG. 13 is a bottom plan view thereof; and,

FIG. 14 is a back elevational view thereof.
